UNITED STATES PATENT OFFICE.

FRANK S. CHURCH, OF CINCINNATI, OHIO, ASSIGNOR OF ONE-HALF TO THE THOS. J. CORCORAN LAMP CO., OF CINCINNATI, OHIO, A CORPORATION OF OHIO.

AIR SPRING.

Original application filed May 31, 1921, Serial No. 473,873. Divided and this application filed April 18, 1922. Serial No. 555,474.

To all whom it may concern:

Be it known that I, FRANK S. CHURCH, a citizen of the United States, residing at Cincinnati, in the county of Hamilton and State of Ohio, have invented a new and useful Air Spring, of which the following is a specification.

This invention relates to an improved air spring of the annular tube diaphragm type disclosed in my copending application serially numbered 473,873, filed May 31, 1921, and of which this application forms a divisional application thereof.

An object of the air spring now to be described is to produce an improved air spring in which the resiliency of action is greatly increased principally during the main or primary shock absorbing action of the spring, but also during the secondary or snubbing action thereof.

This and other objects are attained in the construction described in the following specification and illustrated in the accompanying drawings in which:

20 Fig. 1 is a sectional elevation of an air spring disclosing a construction embodying the improvements of the present invention, showing the spring in normal condition.

Fig. 2 is a view of the construction shown in Fig. 1, but showing in full lines the parts moved to occupy the positions assumed during a movement impelled by a main or primary shock, and showing in dotted lines the position assumed by the parts upon a snubbing movement responsive to a secondary or rebound shock, with an added feature of my invention which I employ to increase the snubbing effect of my improved spring construction.

40 In my invention as I have disclosed it herein, the outer member 23 is of dome shape form, being somewhat elongated above an air cushion 24 which is located within the lower enlarged open end of the member 23. The lower edge of the outer member is provided with a spring attaching bracket 25 which extends downwardly for attachment thereto of the end of the spring of the vehicle, as shown. The air cushion 24 is located within the enlarged lower portion 26 of the outer member 23, the upper portion joining the lower portion by means of a reverse curve.

Cushion 24 of this form of my invention

is somewhat different from the annular tube type of my invention as disclosed in the copending application referred to above, in that it has the shape somewhat of a collapsed hollow sphere with diametrically opposite holes located centrally and in registration with one another when the cushion sides are collapsed as shown in the drawings. Through the holes of the collapsed cushion a screw threaded stud 27 is passed, this stud screwing into an interiorly located hollow nut or disc 28 which, through a method I will not describe herein, is placed in the cushion at the time it is made. The lower end of the stud 27, which projects beyond the cushion, screws into a spring attaching member 29 which clamps the lower part of the cushion between it and the nut 28. This member 29 has an outwardly and downwardly curved surface 30 over which the cushion rolls when the spring operates, as will be hereinafter described. Stud 27 extends above the cushion at its upper side and screws into a hollow substantially spherical air reservoir 31 which is located and moves within the elongated outer member 23 as the cushion moves, the reservoir clamping the upper part of the cushion against the nut.

Through the center of stud 27 an air passage 32 is provided, the lower end of the passage communicating with the inflating valve 33 similar to the usual tire inflating valve, and the upper end having a valve 34 therein for a purpose to be hereinafter described. Transversely extending air passages 35 formed in the nut and stud, communicate with the central passage 32 of the stud, and located in the passages is a spring tensioning pin 36 which retains the lower end of a spring 37, the lower end of which is connected with valve 34 to retain it yieldingly on its seat in the stud 27. The valve 34 I have shown provided with a bleeder passage 38, the purpose of which will also be hereinafter described. In the form of my invention shown in Fig. 1, a breather tube 39 is provided in the outer member to allow air to be discharged from and to enter the outer member in response to movements of the spring members, porous material being provided in the breather to exclude dust. In the form of my invention shown in Fig. 2 I have shown the

Fig. 1 construction provided with a snubbing valve of the same construction as that shown in the copending application to which I have referred above. This snubbing valve 8 is located in the top of the member 23 for the purpose of utilizing the space within the dome, between chamber 31 and the top of the dome, for a snubbing chamber in which the compression and rarefaction phenomena of air is utilized in the snubbing action of the spring. The type of valve I have shown consists of a valve cap 16 screwed into a boss 17 in the top of the dome, the cap being hollow and having vent passages 18 beneath its top 19. Between the cap 16 and passing through the boss 17, a passage 20 is formed, having a frustoconically enlarged upper end in which a conical valve 21 is seated. The valve is provided with a stem which fits loosely within the cap 16 and which is hollow to contain a spring 22, which, being located between the cap and valve, retains the valve yieldingly on its seat. The stem is of sufficient length to abut the underside of the cap when the valve is open, and yet not stop the flow of air through the valve by bringing it into contact with the cap projection.

In the operation of the form of my invention shown in Figs. 1 and 2, I will first describe the operation of the invention in the form in which it is shown in Fig. 1. The spring attaching bracket 25 is connected with the chassis of a vehicle and the spring attaching member 29 is connected with the running gear of the vehicle. Air is then pumped through valve 33 until the cushion 24 and reservoir 31 are filled with air to the required pressure to bring the parts to normal position, as shown in Fig. 3, the air entering the cushion through the passages 32 and 35 and entering reservoir 31 by lifting valve 34, bleeder passage 38 assuring uniform pressure in the reservoir and cushion.

With the parts thus brought to normal position, any main or primary shock transmitted to the running gear through its member 40, will cause the member 30 to move upwardly, thus carrying with it reservoir 31 and nut 28. The cushion will hence be rolled over the curved surface 30 of member 29 and the curved inner surfaces of portion 26 of member 23, as shown in full lines in Fig. 2. During this movement some of the air in member 23 is displaced through the breather 39 and the air in cushion 24 is compressed and discharged through valve 34 into reservoir 31 where the pressures of the reservoir and cushion are equalized. Having been equalized, the valve 34 will close and the cushion will restore the members to normal position, but the rebound or secondary shock will take place to cause the parts to move to the dotted line positions shown in

Fig. 2, the cushion resisting the movement by again being compressed, but in the reverse direction, the air above reservoir 31 again being restored through breather 39 as a partial rarefaction thereof within member 23 takes place. In the auxiliary reservoir construction of the form shown I have provided a means for giving a decided increase in air cushion volume without increasing the size of the cushion over that shown in the application to which I have referred above, but by doing so I have greatly increased the degree of flexibility or travel of the air spring members relatively to one another.

In the form shown in Fig. 2, the operation just described in connection with the form shown in Fig. 1, takes place in an identical manner, except as to the snubbing action afforded by the valve 8 in connection with the rebound movements of the parts as has been described in connection with the description of the form set forth in my copending application. In the Fig. 2 form of my invention the breather 39 is utilized as a bleeder passage to restore normal pressure within member 23.

Various departures may be made from the exact embodiment of the invention as disclosed herein, without deviating from the spirit and scope of my invention as set forth in the appended claims, but it will be readily understood that in any form of its embodiment the invention as it is set forth herein consists in providing a spring of the type herein described, with an auxiliary or reserve supply reservoir for rendering the spring additionally flexible and sensitive in both main and rebound shock impelled movements thereof.

Having thus described my invention what I claim is:

1. In combination within an air spring an outer shell like member, an air cushion located in one end of the outer member, a hollow inner member located within the outer member, communicating with the interior of the cushion and movable within the outer member, and a valve between the inner member and the cushion adapted to permit a discharge of air from the cushion to the inner member when the cushion is compressed in response to a shock impelled movement thereof, said valve having a bleeder passage therein to permit restoration of air from the inner member to the cushion upon movement of the parts to normal position.

2. An air spring for vehicles comprising a substantially annular air cushion, an element mounting the cushion and having curved surfaces adapted to engage a portion of the curved walls thereof, and a member surrounding the cushion and having curved surfaces adapted to engage a portion of the

curved walls thereof opposite that portion engaged by the first mentioned member, said element consisting of a solid member located on one side of the cushion and a hollow member located on the other side of the cushion and having its interior in communication with the interior of the cushion, and a valve between the cushion and the

hollow member adapted to permit free passage of air from the cushion to the hollow member upon movement to an abnormal position, and restricted passage of air from the hollow member to the cushion upon return movement to normal position. ¹⁰

FRANK S. CHURCH.
